Inventor:
Broderick Haskell,
by Michaelow, Attorney

UNITED STATES PATENT OFFICE.

BRODERICK HASKELL, OF FRANKLIN, PENNSYLVANIA.

TRUCK BOLSTER.

Application filed June 8, 1926. Serial No. 114,521.

This invention relates to bolsters for railway cars and more especially to a truck bolster built of cast or pressed steel.

The objects of the invention are:—

- 5 First, to construct a hollow truck bolster which is provided with a recess, pocket or female member of a bearing within the body of the bolster and entirely below the upper face or surface of the bolster to receive a coacting male member of a bearing on a cooperating body bolster, said recess, pocket or female member being formed by a separate element and seated wholly within the body and rigidly secured to said bolster.
- 10 Second, to provide a hollow truck bolster with a recess, pocket or female member of a bearing and capable of securing said female member to any depth within said bolster without weakening the carrying capacity of said bolster and furthermore reinforcing the strength of the bolster due to the thickness and uniform and proper distribution of the metal at the juncture of said female bearing member with the upper section or top of said bolster.
- 15 Third, to provide a hollow truck bolster of the character indicated with a female member which can be made of any depth without altering the location or point at which the load is applied or carried by the bolster and the strength of said bolster is not sacrificed by the depth or location of said female bearing member.
- 20 Fourth, to provide a hollow truck bolster with a removable and renewable female bearing element extending into the body of the bolster and supported from the upper face of said bolster, whereby a fractured or worn out bearing element may be detached and another quickly substituted therefor without discarding the other sections of the bolster as is common practice with the present type of truck bolsters.
- 25 Fifth, to construct a hollow or boxed truck bolster of cast or pressed steel having a female bearing member inserted into the body of the bolster and suspended from the top of the side walls and upper face of the bolster.
- 30 Sixth, to provide a construction and arrangement of truck bolster better adapted to be cast in steel and capable of greatly reducing the difficulties of shrinkage, cracks or fractures inherent and usually met with in the art of steel casting.

Seventh, other objects and advantages of construction and arrangement of the several elements comprising the truck bolster will be apparent from the detailed description and manner of operation of the same.

The invention consists of structural characteristics and relative arrangement of elements which will be hereinafter more fully described and particularly pointed out in the appended claims.

In the drawings in which similar reference characters indicate the same parts in the several figures:

Figure 1 is a top plan view of the improved truck bolster partly in section when made of cast steel.

Figure 2 is a side elevation of the bolster shown in Figure 1 partly in section combined with its cooperating body bolster.

Figure 3 is a section on line III—III of Figure 1.

Figure 4 is a top plan view of the truck bolster when made of pressed steel.

Figure 5 is a side elevation of the bolster shown in Figure 4 partly in section combined with its cooperating body bolster.

Figure 6 is a section on line VI—VI of Figure 4.

Referring to Figures 1, 2 and 3 of the drawings, 10 is a hollow or boxed type of truck bolster preferably made of cast steel and provided with the top 11, bottom 12, sides 13, 13, and ends 14, 14. The top 11, bottom 12, sides 13, 13 and ends 14, 14, are provided with openings 15, 15, 16, 16, 17, 17 and 18, 18, for the purpose of reducing the weight and cost of manufacture of the bolster, and at the same time providing means for the removal of the broken cores from the casting of said bolster.

The top 11 of the bolster midway between the ends 14, 14 and sides 13, 13, is provided with a circular opening 19 in which is seated or supported wholly within the hollow bolster a pocket or female member of a center bearing 20, said member consisting preferably of a hollow cylinder 21 having a bottom 22, sides 23 and an open top 24 provided with an outwardly projecting flange 25 extending to the sides 13, 13 and seated on and removably attached by rivets or bolts 26 to the outer surface of the top 11 adjacent to the circular opening 19, as indicated. This construction and disposition of the female bearing member 20 enables the

same to be supported from the upper face 11 and suspended from the top of the sides 13, 13 and flange of the truck bolster, thereby transferring and distributing the load 5 on the body bolster 27 over the middle section of face or top 11 of the truck bolster 10, and the projecting flange 25 at the same time greatly strengthens and reinforces that section of the bolster which has been weakened due to providing the opening 19 for the reception of said bearing 20.

Cooperating with the above described truck bolster 10 is a hollow body bolster 27 having rigidly attached to its under side by 15 rivets 28 or other means, a downwardly projecting hollow male member 29 which is adapted to be seated and supported in the pocket or female bearing member 20 of truck bolster 10 and permitting said body bolster 20 27 to properly and easily swing through a small arc, as required in this class of railway car appliances, and needs no further disclosure. The bottom and side walls of 25 said hollow projecting male member 29 of the body bolster 27 are preferably provided with openings 30, 30, through which may 30 pass any grease or lubricant stored in said hollow male member 29, said grease or lubricant passing into the center bearing 20 of the truck bolster 10 and between the contiguous side walls and bottoms of the pocket 35 or female bearing member 20 and male member 29, the grease being supplied to the hollow male member 29 through the opening 31 (see Figure 3) communicating with the interior of the hollow body bolster 27.

In Figures 4, 5 and 6 is shown substantially the same invention as described with reference to Figures 1, 2 and 3, except the 40 truck bolster 101 is made of pressed steel and consists, as shown, of top 111, bottom 121, sides 131, 131, and ends 141, joined together by rivets 132, 132, to form an elongated hollow or box-like structure, the top 45 111 of which is provided with a central opening 191 in which is seated the pocket or female bearing member 201 removably secured by rivets 261 passing through the outwardly projecting flange 251 and top surface 111, in the same manner and for the purpose as hereinbefore explained.

The body bolster 271, shown in Figure 5, may be of the same construction and arrangement as that of the body bolster 27, shown and described with reference to Figure 2, and needs no further disclosure as to its detail construction or manner of co-operation with the truck bolster 101.

From the foregoing disclosure it will be seen that all the objects and advantages recited in the statement of invention have been fully and efficiently carried out and a cast or pressed steel truck bolster has been devised in which an independently removable pocket, recess, well, or female bearing

member of a center bearing of any desired depth, and wholly within said bolster, can be effected without weakening said bolster, but on the contrary strengthening said bolster with the use of a minimum of additional metal and cost of manufacture.

While I have shown and described the preferred forms of the invention, it will be readily understood that many changes and arrangements will readily suggest themselves without departing from the spirit of the disclosed invention or changing the function and cooperation of the elements as expressed in the claims.

What I claim is:

1. A truck bolster comprising a body section having a top, bottom and ends, said top having an opening between said ends, a female member of a bearing within the body section and consisting of a hollow seat having a bottom at one end and an open top provided with an outwardly projecting flange seated on and attached to the surface of said top adjacent to said opening.

2. A truck bolster comprising a hollow body section having a top, bottom and ends, said top having a circular opening between said ends, a female member of a bearing within the hollow body section and consisting of a hollow cylinder having a closed bottom at one end and an open top provided with an outwardly projecting flange seated on and attached to the surface of said top adjacent to said circular opening.

3. A truck bolster comprising a hollow body section having a top, bottom and ends, said top having a centrally disposed circular opening midway between said ends, a female member of a bearing wholly within the hollow body section and consisting of a hollow imperforate cylinder having a closed bottom at one end and an open top provided with a circular and outwardly projecting flange seated on and attached to the upper surface of said top adjacent to said circular opening.

4. A truck bolster comprising a hollow metallic body section having a top, bottom, sides and ends, said top having a circular opening centrally disposed with respect to said ends and sides, a female member of a bearing wholly within the hollow body section and consisting of an imperforate hollow cylinder having a closed bottom at one end and an open top provided with an outwardly projecting flange seated on and attached to the top surface of said sides and top adjacent to said circular opening.

5. A truck bolster comprising a hollow body section having a top, bottom and ends, said top having a circular opening between said ends, an imperforate pocket wholly within the hollow body section and consisting of a hollow cylinder having a closed bottom at one end and an open top provided

with an outwardly projecting flange seated on and removably attached to the top surface of said top adjacent to said circular opening.

5 6. A truck bolster comprising a hollow body section having a top, bottom and ends, said top having a circular opening between said ends, an imperforate pocket wholly within and supported from the upper face

of the hollow body section and consisting of 10 a hollow cylinder having a closed bottom at one end and an open top provided with an outwardly projecting flange seated on and attached to the top surface of said top adjacent to said circular opening.

15 In testimony whereof I hereto affix my signature.

BRODERICK HASKELL.
